UNITED STATES PATENT OFFICE.

EULALIO MEDINA, OF DOUGLAS, ARIZONA.

WATER-JACKET.

1,143,642.

Specification of Letters Patent. Patented June 22, 1915.

Application filed December 31, 1914. Serial No. 879,942.

To all whom it may concern:

Be it known that I, EULALIO MEDINA, a citizen of the Republic of Mexico, residing at Douglas, in the county of Cochise and State of Arizona, have invented certain new and useful Improvements in Water-Jackets, of which the following is a specification, reference being had therein to the accompanying drawing.

10 This invention relates to a water jacket for blast furnaces and has for its principal object the production of a jacket which may be supported in a suitable manner adjacent a tap opening so that when the molten material, either glass, iron, steel or the like is withdrawn from the interior of the furnace, it may come into engagement with the water jacket and be held thereby.

Another object of this invention is the production of a U-shaped water jacket positioned adjacent the tap opening of the furnace jacket so as to easily catch the heated material which is being withdrawn from the furnace for chilling the same owing to the fact that the water jacket is provided with a plurality of pipes attached thereto for allowing the free circulation of water therethrough.

Still another object of this invention is the production of a water jacket having a pair of detachable caps, these caps being so formed as to engage the open portions of the water jacket thereby forming a closure for the same and also provided with openings for allowing suitable pipes to be attached thereto for causing a circulation of water within the jacket.

With these and other objects in view this invention consists of certain novel combinations, constructions, and arrangements of parts as will be hereinafter fully described and claimed.

In the accompanying drawings: Figure 1 is a front elevation of a portion of a furnace showing the water jacket attached thereto and being positioned around the cap opening so as to engage the heated material withdrawn from the interior of the furnace. Fig. 2 is a section taken on the line 2—2 of Fig. 1. Fig. 3 is a detailed side elevation of the water jacket showing the circulation pipes connected thereto, broken away. Fig. 4 is a section taken on the line 4—4 of Fig. 3, looking in the direction of the arrows. Fig. 5 is a detailed top plan view of the water jacket. Fig. 6 is an enlarged sec-

tional view through a portion of the water jacket and one of the caps illustrating the manner in which one of the circulation pipes is connected to the cap. Fig. 7 is a section taken on line 7—7 of Fig. 3 looking in the direction of the arrow. Fig. 8 is a detailed perspective view of the interior of one of the caps.

Referring to the accompanying drawings by numerals 1 designates in general the furnace which comprises the usual base jacket 2 for the usual side walls 3 and forward wall 4 thereby forming the usual jacket having the tap plate 5 forming the tap opening 6. This tap plate 5 is held in engagement with the forward wall 4 of the jacket by means of the flange 7 which is held in engagement with the flange 8 and the forward wall 4 by means of the rivets 9.

The water jacket of this invention is adapted to be supported in any suitable manner not deemed necessary to be herein disclosed upon the forward portion of the wall 4 of the furnace jacket so as to surround the tap opening 6. This water jacket comprises a U-shaped hollow body 10 which is elongated so as to extend for a distance beyond the forward wall 4. This hollow water jacket is provided at its upper portion with an elongated flange 11 extending longitudinally along the upper portion of the water jacket so as to be positioned in a horizontal plane. Furthermore, this water jacket 10 may be provided with an inwardly extending shelf 12 formed upon the opposite side of the jacket to the side upon which the flange 11 is formed. This water jacket 10 is also provided at its lower portions with the necks 13 for the reception of 95 the pipes 14.

In order to form closures for the upper open portions of the water jacket 10, there is provided a pair of caps 15. Each cap 15 is substantially semi-circular in cross-section 100 and is elongated so as to be of the same length as the length of the water jacket 10. Each cap 15 is provided with a flange 16 formed integral upon one side thereof and extending at right angles thereto so as to rest upon the longitudinal flange 11 of the water jacket 10. This flange 16 is also provided with apertures 17 which are adapted to register with the apertures 18, formed in the longitudinal flange 11 of the water jacket 110 10 for the reception of the bolts 19. When the cap is placed upon the upper portion of

the water jacket, the flanges will engage each other so as to allow the apertures 17 to register with the apertures 18 and thus the retaining bolts may be easily passed therethrough for securing the cap upon the water jacket. This cap 15 is also provided with inwardly extending lugs 20 having openings 21 formed therein to communicate with the threaded openings 22 formed in the shelf 10 12. The screws 23 may be passed through the openings 21 and engage the threaded openings 22 for positively retaining the cap in position. This cap is also provided with a threaded neck 24 formed adjacent each end 15 thereof for receiving the pipe 25. Since the pipes 14 and 25 remain in engagement with the water jacket 10 and caps 15 respectively, the circulation of water may be maintained within the jacket. Since this jacket is supported around the tap opening 6, the heated material which may be either glass, steel, iron, or the like, when drawn from the interior of the furnace 1 through the tap opening 6 will be caught and supported by the 20 water jacket 10 whereby this material will be chilled as desired.

From the foregoing description it will be seen that a simple and efficient water jacket has been produced which is adapted to be supported adjacent the tap opening of a blast furnace for receiving the material which is being drawn from the furnace for chilling the same but which is provided with a simple and efficient means for maintaining 30 the circulation of water therethrough for causing the same to remain in a chilled condition. Furthermore, the water jacket is also provided with detachable caps which are adapted to be bolted in engagement therewith for forming a substantial one-piece structure and which may be easily removed when necessary for having access to the interior of the water jacket or for the purpose of facilitating the assembling of the same.

45 What I claim is:—

1. A water jacket of the class described comprising a U-shaped hollow body, said body being adapted to be supported adjacent a tap opening of a blast furnace, said water jacket having open upper portions and a plurality of detachable caps secured to the upper portions of said water jacket for closing the open portions, and means connected to said water jacket and to said caps for 50 maintaining a circulation within said water jacket whereby the water jacket will remain in a chilled condition.

2. A water jacket of the class described comprising a U-shaped elongated body, said

body being adapted to be supported adjacent a tap opening of a blast furnace, said body having open upper portions, integral flanges formed upon side portions of said body and extending at right angles thereto, a plurality of elongated semi-circular caps positioned upon the upper portions of said water jacket, said caps provided with integral flanges extending at right angles thereto and being adapted to rest upon the flanges of said body, the flanges of said body and the flanges of 60 said caps provided with registering openings, means passing through said openings for retaining the flanges in engagement with each other, said body also provided with inwardly extending shelves, said caps provided with inwardly extending lugs, said lugs and said shelves provided with registering openings, means passing through said openings for securing the caps in positive 65 engagement with said water jacket, said caps provided with enlarged threaded necks and a plurality of pipes engaging said necks and said body whereby a circulation of water may be maintained within said water jacket for causing the same to remain in a chilled 70 condition.

3. A water jacket of the class described comprising a U-shaped hollow body, said jacket being adapted to be supported adjacent the tap opening of a blast furnace, said body being elongated, said water jacket having open upper portions, means removably carried by the upper portions of said jacket for closing the open upper portions thereof, whereby access may be had to the interior 90 of the jacket when necessary, said water jacket being adapted to engage the material withdrawn from the furnace, and means carried by said water jacket for maintaining a circulation, thereby causing the water 95 jacket to remain in a chilled condition.

4. A water jacket of the class described comprising a body having open outer portions whereby access may be had to the interior of said body for cleaning or repairing 100 the same when necessary, means for closing said open outer portions, said body being adapted to be supported adjacent the tap opening of a blast furnace, and means connected to said water jacket for maintaining 105 a circulation, whereby the water jacket will remain in a chilled condition.

In testimony whereof I hereunto affix my signature in presence of two witnesses.

EULALIO MEDINA.
